UNITED STATES PATENT OFFICE.

JOSEPH G. CRATE, OF WOODSTOWN, AND JAMES F. MORELL, OF CAMDEN, N. J.

CAR-STARTER.

SPECIFICATION forming part of Letters Patent No. 284,948, dated September 11, 1883.

Application filed May 16, 1883. (No model.)

To all whom it may concern:

Be it known that we, JOSEPH G. CRATE and JAMES F. MORELL, citizens of the United States, residing at Woodstown and Camden, in 5 the counties of Salem and Camden and State of New Jersey, have invented certain new and useful Improvements in Car-Starters, of which the following is a description.

This invention relates to that class of devices which are employed to arrest the motion of street-cars, and apply the power thus expended to start or assist in starting the car.

The aim of the invention is to provide a simple and reliable mechanism for the purpose named, and to adapt the same for instantaneous adjustment, so as to operate the same on a car traveling in both directions.

Referring to the accompanying drawings, Figure 1 represents a bottom plan view of a 20 car-frame provided with our improvement. Fig. 2 represents a longitudinal central section of the same on the line *xx*. Fig. 3 represents a vertical section on the line *yy*.

Referring to the drawings, A represents the 25 frame of the car, and B the two horizontal axles, mounted in fixed bearings beneath opposite ends of the frame, and provided with the wheels C, secured rigidly to their ends. The foregoing parts are of ordinary construction and arrangement.

In applying our improvement we secure to the axle B at one end of the car, at a suitable distance apart, two beveled-gear wheels, D and D', having the teeth upon their inner 35 faces. Lengthwise beneath the car, preferably at or near the center, we mount a shaft, E, extending from end to end of the frame, and sustained at its center in a vertically-pivoted yoke, F, and at its two ends in the lower extremities 40 of upright hand-levers G, pivoted to the ends of the frame and extending upward within reach of the attendant upon the platform. The yoke F serves as a central support for the shaft, and by reason of its vertical pivots it is free 45 to rock in a horizontal direction, thus permitting the operator to move the ends of the shaft laterally by means of the hand-levers, the two ends swinging, of course, in opposite directions. To one end of the shaft E we secure rigidly a 50 beveled pinion, H, adapted to engage with one or the other of the wheels D D', according

as the shaft is moved to the right or left. We also secure to the shaft E, near its center, a powerful coiled spring, I, one end of which is secured to the shaft, while the opposite end is 55 secured to the yoke F or to the car-frame. If, while the car is moving in the direction indicated by the arrow in Fig. 1, the operator by means of either of the hand-levers moves the shaft E in such manner as to throw the 60 pinion H into an engagement with the wheel D', motion will be communicated from the car-wheel, through the wheel D', to the pinion H, the effect of which will be to rotate the shaft E and wind up the spring I, the resistance 65 of the spring serving to gradually arrest the motion of the car, while the momentum of the car, on the other hand, will place the spring under a high degree of tension. If, now, while the spring is thus under tension, the operator 70 moves the lever so as to shift the shaft in the opposite direction, the pinion H will be disengaged from the wheel D' and engage with the wheel D, whereupon the energy of the spring exerted through the intermediate parts upon 75 the wheel D will tend to turn the car-axle and wheels in the forward direction, thereby starting or assisting to start the car.

In order to secure the proper working of the apparatus, it is necessary that means shall be 80 provided for maintaining the spring under tension and prevent the rotation of its shaft during the time that the pinion H is being shifted from the wheel D' to the wheel D. For this purpose we provide each end of the shaft 85 E with a ratchet-wheel, J, and provide each of the hand-levers G with a pawl, K, to engage in said ratchet-wheel, the pawl thus applied serving, while in engagement, to hold the shaft against a backward rotation, and thus keep 90 the spring under tension. Each pawl is acted upon by a spring, L, to cause its engagement, and is combined with a thumb-lever, M, pivoted to the hand-lever and extended upward, as shown, so that the attendant by operating 95 this secondary lever M may disengage the pawl from the ratchet-wheel to permit the spring to turn the shaft when the starting of the car is to be effected. Owing to the fact that the pawl is pivoted upon the hand-lever, 100 which also carries the ratchet-wheel shaft, it will be seen that the lateral movement of the

shaft in no manner affects the engagement of the pawl, which moves with the lever and holds the shaft against rotation during the time that it is being moved to reverse the gear.

5 In order that the pawl and ratchet at one end of the car may not interfere with the operation of that at the other, we provide each hand-lever with a link, O, or equivalent device, to engage with the thumb-lever and hold 10 its pawl out of action.

For the purpose of holding the pinion H in engagement with one or the other of the wheels D D', or in an intermediate position, as may be required, we provide a locking device for 15 each of the hand-levers G, to hold the same in the different positions required. This locking device may be of any suitable character; but it is preferred to employ the particular form of device represented in the drawings, 20 consisting simply of an angular foot-lever, P, mounted upon the frame and provided at its upper end with a stud or projection to enter notches Q in the hand-lever. Each lever is provided with three of these notches—one to 25 hold the pinion in engagement with the wheel D', another to hold it in engagement with the wheel D, and the third to hold it in an intermediate position, the last-named being the position in which it stands during the time 30 that the car is in motion. For the purpose of holding either of these locking-dogs out of action at will, we provide at each end of the car a pivoted button, R, to engage over the lower end of the dog, as shown. When the attendant 35 is located at one end of the car, the devices for locking the hand-lever at the opposite end, as well as the pawl for locking the corresponding ratchet-wheel, are thrown out of action.

The action of the apparatus is as follows: 40 The car being in motion and the pinion H in its intermediate position, as represented in Fig. 1, and it being desired to arrest the motion of the car, the attendant, located at either end of the car, throws the hand-lever to the 45 right or the left, according to the direction in which the car is moving, so as to cause the gearing to wind the spring, the tension of which is maintained by the pawl. The parts remain in this position until the car is to be 50 started again, when the attendant moves the hand-lever so as to reverse the connection of the gearing, and thereby connect the spring in such manner that its force will be expended to urge the car forward. He next operates 55 the finger-lever, thereby lifting the pawl and permitting the force of the spring to be applied to the gearing.

It will be observed that our arrangement of 60 gearing may be employed with equal facility whether the car be moved in one direction or in the other, that the full force of the spring is utilized, and that the parts operate without sudden strain or shock.

While we have described the shaft E as extending through the car from end to end, in 65 order that the starting device may operate from either end of the car at will, it is manifest

that on those cars which run always in the same direction, or with the same end forward, the shaft may be terminated at the center, and 70 the hand-lever and connections at the rear end omitted.

The present invention is restricted to those matters and things which are hereinafter claimed, and as to all matters which may be 75 described or shown, but which are not claimed, the right is reserved to make the same the subject of a separate application.

Having thus described our invention, what we claim is—

1. The car-axle having two gear-wheels secured rigidly thereto, in combination with the longitudinal shaft, the spring, the gear-wheel attached to said shaft between the wheels upon the axle and adapted for engagement 85 with said wheels alternately, and a manual lever for effecting the lateral motion of the shaft, substantially as described, whereby the momentum of the car is applied to wind the spring, and the power of the spring in turn 90 applied to propel the car.

2. In combination with the car-axle, the longitudinal shaft extending to the two ends of the car and movable laterally around a central point in its length, the reversible gear 95 to connect the shaft and axle, the spring, and independent manual devices at the two ends of the car to move the shaft, whereby the winding and driving devices may be actuated from either end of the car at will.

3. The car-axle, the gear-wheel secured rigidly thereon, the longitudinal shaft movable in a horizontal direction, the gear-wheel and spring secured upon said shaft, the upright manual lever to sustain and move the 105 shaft, the devices attached to said lever for the purpose of preventing the rotation of the shaft, and mechanism, substantially as described, for locking said hand-lever in different positions, whereby the gear may be 110 adjusted and maintained in an inoperative position, or in position to wind the spring, or in position to start the car.

4. In combination with the longitudinal laterally-movable shaft and the gear for connecting the same with the car-axle, the vertically-pivoted supporting-yoke, and the spring secured at one end to the shaft and at the opposite end to said yoke.

5. In combination with the car-axle and its 120 gears, the longitudinal laterally-movable shaft and its gear-wheel, a spring connected with said shaft, and two independent hand-levers mounted at opposite ends of said shaft for the purpose of moving the same laterally, each hand-lever provided with a device to lock the shaft against rotation, and combined with a locking-dog, substantially as described, adapted to hold the lever in either of the three positions named.

6. The combination, in a car, of the longitudinal spring-actuated shaft provided with the gear-wheel and ratchet-wheels, the axle provided with gear-wheels, the two hand-levers

at opposite ends of the shaft, a pawl upon each hand-lever to engage the corresponding ratchet-wheel, means, substantially as described, for holding said pawl out of action, 5 and a locking-dog, substantially as described, adapted to lock the lever in either of the three positions as stated, whereby either hand-lever and its connections may be secured in an inoperative position and the mechanism controlled wholly from the opposite end of the car.

7. In combination with the spring-actuated shaft and the reversible gear for connecting the same with the car-axle, the hand-lever for

effecting a lateral movement of the shaft, the dog pivoted upon the car to lock the lever in 15 different positions, and the device for securing said dog in an inoperative position.
